INVENTOR
FRANCISCO LOPES SPINOLA
ATTORNEY

Manuel C. Rosa

UNITED STATES PATENT OFFICE.

FRANCISCO LOPEZ SPINOLA, OF FALL RIVER, MASSACHUSETTS.

SAFETY LIGHTER FOR GAS STOVES OR THE LIKE.

Application filed August 20, 1928. Serial No. 300,837.

This invention relates to devices for lighting the burners of a gas stove, and more particularly to a pilot light which is kept burning for the purpose of lighting the gas whenever it is turned on.

It is an object of my invention to provide a pilot light which is simple in structure and reliable in operation.

It is another object of my invention to provide an individual pilot light for each of the gas burners which is automatically controlled by the turning of the valve handle for each of the burners whereupon the pilot light is jetted outwardly into the burner. The pilot light is so positioned that it will light the gas whenever it is turned on, either by accident or otherwise.

Other objects and advantages will appear from the detailed description which follows taken in conjunction with the accompanying drawing.

I attain these objects and advantages by means of the device illustrated in the drawing wherein

Figure 1 is a plan view of a gas stove with the invention applied thereto.

Figure 2 is an enlarged detailed view showing the automatic control means between the valve for the gas burner and the valve for the pilot light, the pilot light being shown equipped with a small guard for preventing its extinguishment by water or other fluids.

Similar numerals refer to similar parts throughout the several views.

Referring to Figure 1, the gas stove is provided with a main supply pipe 2, the branch supply pipes 3 and the burners 4. A valve cock 5 with the handle lever 6 is provided for each of said burners. The main supply pipe 2 is provided with a branch pipe 7 to which a smaller pipe 8 is secured by means of the T union 9. The pipe 8 is parallel to the supply pipe 2 and from it run the feed pipes 10 for each of the pilot lights 12.

As shown in Figure 2, each of the feed pipes 10 is provided with a valve means 13 of usual construction having a spring actuated closure 14. The supply pipe 2 is provided on its upper surface with cupped lugs 15 to which are secured springs 16. The cupped lugs may be made integral with the

supply pipe 2 or may be attached thereto by means of a separate band. To the upper end of the helical spring 16 is secured the upper portion of the lever 17. The lever 17 is substantially S-shaped and is attached to or adapted to contact with the handle 22 of the spring urged closure 14 at its extremity 23. The relation between the spring 16, the lever 17 and the valve means 13 for the pilot light is such that when the valve cock 5 is closed there is no pressure against the spring urged closure 14.

It will be appreciated that on opening the valve cock 5 the handle lever 6 will contact the flat portion 18 of the lever 17 and will depress the lever 17 which in turn depresses the spring urged means 14 which causes the pilot light to be jetted into the surrounding gas burner. As shown, each of said pilot lights is centrally disposed within each of said gas burners 4. The feed pipes 12 are each provided with a small upright pipe 20 having a tapered end with openings therein to form the pilot light. The upper extremity of the tapered end is provided with a guard 21 which resembles an inverted saucer.

As shown in Figure 2, the burner 4 is not shown with the grating which is generally used thereon and which would clear the guard 21. In any event, the pilot light should be so constructed that the guard does not interfere with any vessels which may be placed on the burner. A further modification may be employed in such a case by securing the guard portion to a helical spring which in turn is secured to the pipe 20 which would allow the guard portion to yield in case it extended above the gas burner.

The operation of the device is as follows. The pilot light remains at all times lighted. When it is necessary to light a gas burner the handle lever is turned as in the general operation of opening the same and in the course of its arcuate path it abuts against the lever secured to the main supply pipe and causes the same to be depressed. As this lever is at all times contacting the spring urged control means on the feed pipe 10, to which the pilot light is attached, the spring urged means releases more gas to the pilot light and causes the pilot light to

become fuller and giving quicker ignition. The contact between the handle lever and the spring urged means associated with the pilot light is made only when the handle 5 lever contacts the lever during its path of turning in either the off to on, or the on to off directions. When the handle lever passes beyond the topmost portion of the lever actuating the pilot light in either direction, the pilot light again burns low. The same results are obtained should the handle lever of the valve cock be turned or moved accidentally. As constructed it will be seen that the juxtaposition of the pilot 10 light to the burner precludes the possibility of escaping gas and renders the gas stove fool proof.

All that has been said above in the description of my preferred embodiment is offered by way of illustration and not limitation. I do not wish to be limited to the exact structure of the preferred embodiment shown and described, or to any particular material used in the construction of parts, 20 or to the design of parts, but desire protection as against any variations in structure or substitution of equivalents which utilize the principle of my invention and fall within the 25

purview of my invention and are within the spirit and scope of the following claim. 30

The invention having been set forth, what is claimed as new and useful is:

A gas stove having in combination gas burners, branch supply pipes therefor, a main supply pipe, an individual pilot light 35 for each gas burner, a substantially parallel feed pipe connected to said main supply pipe, branch feed pipes on said parallel feed pipe for said pilot lights, said individual pilot lights being positioned centrally of said gas burners, a guard on each of said pilot lights to protect it against liquids, said feed pipes being provided with a spring urged control means for each pilot light, control means for each pilot light, said gas burners having each an individual valve cock provided with a handle, a substantially S-shaped means contacting said spring urged control means and passing under said handle, said S-shaped means being so positioned that it is adapted to be depressed by the turning of said handle. 40

Signed at Fall River, in the county of Bristol, State of Massachusetts, this ninth day of August, 1928.

FRANCISCO LOPES SPINOLA. 50
